A. K. MILLER

SOUND AMPLIFIER

Filed March 22, 1921

Inventor:
Alfred K. Miller

By James T. Miller,

his Attorney

UNITED STATES PATENT OFFICE.

ALFRED K. MILLER, OF LOS ANGELES, CALIFORNIA.

SOUND AMPLIFIER.

Application filed March 22, 1921. Serial No. 454,534.

To all whom it may concern:

Be it known that I, ALFRED K. MILLER, a citizen of the United States, residing in Los Angeles, county of Los Angeles, State of California, have invented new and useful Improvements in Sound Amplifiers, of which the following is a specification.

This invention relates to devices adapted to amplify sound; and the invention is 10 adapted to be used in connection with any kind of sound producing apparatus, whether human or artificial, and in connection with all various kinds of artificial sound producing apparatus. In the particular 15 embodiment of the invention hereinafter described and illustrated in the accompanying drawings, the sound amplifier is shown specifically adapted to be used in connection with a phonograph, but it will be particularly understood that the invention is not 20 restricted to such use, such particular application of the device being only used in this specification as illustrative and for the purpose of making my invention clear and 25 intelligible by means of a typical specific application.

It is not only an object of my present invention to provide a device for amplifying sounds but also a device which will, in accomplishing its purpose of amplification, not 30 introduce into the amplified sounds other sounds which are foreign to those received by the amplifier, and which may be objectionable. On the other hand, it is, in some 35 instances at least, an object of the invention to provide the device in such form that it will (relatively speaking) qualify the amplified sounds by bringing out more strongly certain kinds of sounds not amplified in 40 an ordinary amplifier or phonograph horn, but weakly amplified, and are therefore comparatively lost or drowned out in the larger amplification of other sounds. The 45 particular construction and design shown in the accompanying drawings and described hereinafter, is one which I have found very effective for the clear amplification of vocal and instrumental sounds and tones of a phonograph; amplifying those sounds and 50 tones and at the same time keeping their

natural and proper qualifications and eliminating a great many of the objectionable sounds and tones that are usually prevalent in phonographic reproductions. For instance, in phonographic reproductions, 55 there is a distinct tonality usually due to the horn or amplifier itself, and is one of the tonalities that enters into that characteristic tone quality that is known as "phonographic." My present sound amplifier does 60 away with such objectionable tone qualifications.

For the purpose of making my invention clear and intelligible I will now proceed to a detailed and specific description of one 65 specific form of sound amplifier that I have found successful in connection with phonograph machines, reference for this purpose being had to the accompanying drawings, in which—

Fig. 1 is an elevation illustrating an arrangement of my sound amplifier with a phonograph machine; Fig. 2 is an enlarged longitudinal central vertical section of the sound amplifier; Fig. 3 is a front end elevation of the same; Fig. 4 is a vertical section taken as indicated by line 4—4 of Fig. 2; Fig. 5 is a plan of the amplifier; Fig. 6 is a section taken as indicated by line 6—6 on Fig. 2; Fig. 7 is a section taken as indicated by line 7—7 on Fig. 2; and Fig. 8 is a horizontal section taken as indicated by line 8—8 on Fig. 2.

In the drawings in Fig. 1 I indicate the elements of a phonograph machine, illustrating the table at 10, a record at 11, a reproducer at R, a tone arm at 12, the rear end of which connects with an elbow at 13, and to the lower end of this elbow 13 my sound amplifier A is connected. It makes 85 no difference in what position the amplifier is placed; but I have shown it placed in such a position that it hangs below the elbow 13; and so shall describe its component parts in that position. The inlet tube or throat 90 of the amplifier is shown at 15, preferably circular and this opens into the amplifier proper as illustrated in the drawings. Immediately under the entering tube 15 the back wall of the amplifier curves somewhat 95 100

inwardly as illustrated at 16, so that the sound waves impinge upon this forwardly curved portion and are thrown outwardly toward the forward opening of the amplifier. In the portion 16 a horizontal section of the wall becomes either flat or slightly convex, rather than concave as it is at other places. This condition is well illustrated in Figs. 5 and 8. From the portion 16 the back wall of the amplifier curves downwardly and forwardly as illustrated at 17 and then somewhat upwardly and forwardly as shown at 18, to the mouth 19. Around the mouth 19 there may be (although I have found that this is not necessary) an inwardly turned flange 20 which reduces the size of the mouth to a diameter substantially less than the diameter of the body of the amplifier directly back of the mouth opening.

The upper wall of the amplifier is a continuation of the forward wall of the tube 15, the wall being curved forwardly and then upwardly as indicated at 21. Side walls as shown at 22 flare forwardly and outwardly toward the mouth. The vertical sections of Figs. 4, 6 and 7 show the general circular or oval formation of the walls when looked at from the forward end.

Across the upper parts of the amplifier opening, and a little forward of a position directly below the forward wall of tube 15, there is a deflector wall 30, whose position and configuration are shown in the drawings. This deflector wall may preferably be made integrally with the body of the device and may preferably have a slightly forwardly curved lip 31 at its lower edge. Wall 30 extends in a curve across the interior of the structure, as it thus shown in Figs. 5 and 8, being concave inwardly and convex outwardly. Its upper edge joins the wall 21 at about the lowermost point of that wall 21; and the lower edge of the deflector walls 30 extends down to a point substantially opposite or perhaps a little below, the upper part of the inwardly curved portion 16 of the back wall. The lower edge 31 of wall 30 stands substantially on the level, or perhaps a little above, the center of the opening 19.

The device which I have described resonates, qualifies, and augments sound waves by its peculiar conformation and not by virtue of any resonant qualities of its walls. It is not necessary, for its full and complete operation that the walls be made of any resonant or vibratory material. So, for the purposes of this device I may and do make the whole device of some suitable material which will furnish a sound reflective surface rather than a sound resonating wall. For many purposes it is preferable to use such a material as I here designate, as thereby all

foreign resonations from the walls of the device are entirely obviated. For instance I make the whole device of a single casting of aluminum with comparatively thick and non-vibratory walls, finishing the interior to a smooth surface.

I have said that it is of no consequence in what relative position this sound amplifier is placed; in the preceding description I have, merely for ease of description, explained the device in one particular position. For the purposes of the following claims, wherever for more specific setting out of the structure it is necessary to describe specific relations of parts, I shall consider the tube 15 to extend in a transverse direction and consider the opening 19 to face in a longitudinal direction; that is, for instance, Fig. 8 is a section on a plane which extends longitudinally from left to right in that figure.

It will be understood however that the invention in its broader aspects is not limited to the particular relative arrangements and combinations herein specifically shown as a particular embodiment, except as specifically limited by the following claims.

Having described a preferred form of my invention, I claim:

1. A sound amplifier, comprising a hollow body with an inlet opening leading downwardly into the rear part of the body, an outlet opening at the forward end of the body facing in a horizontal direction, and the wall of the body extending continuously and smoothly from the rear edge of the inlet opening first downwardly and then curving into a horizontal direction and then curving upwardly where it comes to the outlet opening, the body having an inwardly hanging flange around the outlet opening to reduce it in size as compared with the immediately adjacent part of the body interior.

2. A sound amplifier, comprising a hollow body with an inlet tube extending downwardly into the rear part of the body, having an outlet opening at its forward end facing in a horizontal direction and having continuous and smoothly extending walls leading from the walls of the inlet tube to the periphery of the outlet opening, the rear wall extending from the rear wall of the inlet tube on in a generally downward direction and bending forwardly and then bending upwardly to the lower edge of the outlet opening, and the wall leading to the upper edge of the outlet opening extending rearwardly and downwardly therefrom in back of the outlet opening and curving and joining the front wall of the inlet tube, and a downwardly extending deflector wall extending from said last mentioned wall near the point where it joins said wall of the inlet tube and lying across the communica-

tion of the inlet tube with the hollow interior of the body, said deflector wall being disposed at the rear of and opposite the outlet opening.

5. A sound amplifier, comprising a hollow body with an inlet tube extending downwardly into the rear part of the body, having an outlet opening at its forward end facing in a horizontal direction and having 10 walls leading from the walls of the inlet tube to the periphery of the outlet opening, the rear wall extending from the rear wall of the inlet tube on in a generally downwardly direction and bending forwardly and then bending upwardly to the lower edge of the outlet opening, and the wall leading to the opposite 15 edge of the outlet opening extending rearwardly and downwardly therefrom in back of the outlet opening and curving and joining the front wall of the inlet tube, the first mentioned wall in its downward extent having a somewhat inwardly convexed portion opposite and directly facing the outlet opening.

15. A sound amplifier, comprising a hollow body with an inlet tube extending downwardly into the rear part of the body, having an outlet opening at its forward end facing in a horizontal direction and having 20 walls leading from the walls of the inlet tube to the periphery of the outlet opening, the rear wall extending from the rear wall of the inlet tube on in a generally downwardly direction and bending forwardly and then bending upwardly to the lower edge of the outlet opening, and the wall leading to the opposite 25 edge of the outlet opening extending rearwardly and downwardly therefrom in back of the outlet opening and curving and joining the front wall of the inlet tube, the first mentioned wall in its downward extent having a somewhat inwardly convexed portion.

4. A sound amplifier, comprising a hollow body with an interior that expands from one end to the other and an outlet opening at its larger end, an inlet opening that leads transversely into the smaller end of the body at one end, the walls of the body extending continuously and smoothly from the inlet opening to the outlet opening, and a deflector extending across the body opening and projecting transversely from the body wall at that side at which the inlet leads in, said deflector 30 being disposed opposite the outlet opening.

5. A sound amplifier, comprising a hollow body with an interior that expands from one end to the other and an outlet opening at its larger end, an inlet opening that leads 35 transversely into the smaller end of the body at one end, and a deflector extending across the body opening and projecting transversely from the body wall at that side at which the inlet leads in, said deflector having a forwardly curved lip along its lower edge.

6. A sound amplifier, comprising a hollow body with an interior that expands from one end to the other and with an outlet opening at its larger end, a transverse inlet tube opening into the interior of the hollow body at the small end thereof, the walls of the tube merging into the walls of the body, one of the body walls having a convexed portion so disposed with respect to the tube and outlet 50 opening that sound waves entering the hollow body through the tube impinge the convex portion and are thereby deflected through the outlet opening.

60. 7. A sound amplifier, comprising a hollow body with an inlet tube extending downwardly into the rear part of the body, having an outlet opening at its forward end facing in a horizontal direction and having walls leading from the walls of the inlet tube

to the periphery of the outlet opening, the 65 rear wall extending from the rear wall of the inlet tube on in a generally downward direction and bending forwardly and then bending upwardly to the lower edge of the outlet opening, and the wall leading to the opposite 70 edge of the outlet opening extending rearwardly and downwardly therefrom in back of the outlet opening and curving and joining the front wall of the inlet tube, the first mentioned wall in its downward extent having a somewhat inwardly convexed portion 75 opposite and directly facing the outlet opening.

8. A sound amplifier, comprising a hollow body with an inlet tube extending downwardly into the rear part of the body, having an outlet opening at its forward end facing in a horizontal direction and having 80 walls leading from the walls of the inlet tube to the periphery of the outlet opening, the rear wall extending from the rear wall of the inlet tube on in a generally downwardly direction and bending forwardly and then bending upwardly to the lower edge of the outlet opening, and the wall leading to the opposite 85 edge of the outlet opening extending rearwardly and downwardly therefrom in back of the outlet opening and curving and joining the front wall of the inlet tube, the first mentioned wall in its downward extent having a somewhat inwardly convexed portion 90 opposite and directly facing the outlet opening.

9. A sound amplifier, comprising a hollow body with an inlet tube extending downwardly into the rear part of the body, having an outlet opening at its forward end facing in a horizontal direction and having 95 walls leading from the walls of the inlet tube to the periphery of the outlet opening, the rear wall extending from the rear wall of the inlet tube on in a generally downwardly direction and bending forwardly and then bending upwardly to the lower edge of the outlet opening, and the wall leading to the opposite 100 edge of the outlet opening extending rearwardly and downwardly therefrom in back of the outlet opening and curving and joining the front wall of the inlet tube, the first mentioned wall in its downward extent having a somewhat inwardly convexed portion 105 opposite and directly facing the outlet opening.

10. A sound amplifier, comprising a hollow body with an interior that expands from one end to the other and with an outlet opening at its larger end, a transverse inlet tube opening into the interior of the hollow body at the small end thereof, the walls of the tube 115

merging into the walls of the body, one of the body walls having a convexed portion so disposed with respect to the tube that sound waves entering the hollow body through the 5 tube impinge and are deflected by the convex portion, and a deflector extending downwardly from the junction of one of the tube walls with one of the body walls, said deflector depending to a point substantially op-

posite the upper extent of said convexed portion. 10

In witness that I claim the foregoing I have hereunto subscribed my name this 17th day of March, 1921.

ALFRED K. MILLER.

Witness:

VIRGINIA BERNINGER.
